United States Patent

Des. 241,072
Patented Aug. 17, 1976

241,072

TELEVISION CAMERA

Renville H. McMann, Jr., New Canaan, Conn., Clyde W. Smith, North Salem, N.Y., and John C. Wistrand, New Canaan, Conn., assignors to Thomson-CSF Laboratories, Inc.

Filed Nov. 29, 1974, Ser. No. 528,129

Term of patent 14 years

Int. Cl. D14—03

U.S. Cl. D26—14 E

FIG. 1

FIG. 2

FIG. 3

FIG. 5

FIG. 4

FIG. 1 is a perspective view of a television camera showing our new design;

FIG. 2 is a top plan view thereof;

FIG. 3 is a front elevational view thereof;

FIG. 4 is a rear elevational view thereof; and

FIG. 5 is a bottom plan view thereof.

We claim:

The ornamental design for a television camera, substantially as shown.
